UNITED STATES PATENT OFFICE.

EDWARD R. KAST, OF PEARL RIVER, NEW YORK, ASSIGNOR TO KAST INSETTING AND GATHERING MACHINE COMPANY, OF NEW YORK, N. Y., A CORPORATION OF DELAWARE.

BOOK-TRIMMER.

1,327,915.

Specification of Letters Patent. Patented Jan. 13, 1920.

Application filed December 24, 1917. Serial No. 208,658.

To all whom it may concern:

Be it known that I, EDWARD R. KAST, a citizen of the United States of America, and a resident of Pearl River, New York, have 5 invented a new and useful Improvement in Book-Trimmers, which invention is fully set forth in the following specification.

The present invention is an improvement in book trimmers, and has for its object to 10 provide a device of the character described which will automatically, speedily, continuously and accurately trim the edges of each book as it is delivered from the book-forming machine.

15 The practice heretofore in connection with books gathered, inset or otherwise assembled, whether the signatures that constitute the book are gathered or inset manually, or mechanically by machines such as illustrated 20 in my Patents Nos. 1,177,524, 1,177,525, and 1,236,181, has been to trim the books in batches on well-known cutting or trimming machines; that is to say, the books are removed from the delivery of the machine, 25 piled on trucks, carried to the trimmer, trimmed in batches, and then carried to the mailing or shipping department. This procedure has entailed great expense, in connection with books like the Saturday Evening Post, for example, which are inset on 30 machines such as illustrated in the patents indicated; to say nothing of the valuable floor space that has heretofore been occupied by huge piles of untrimmed books waiting 35 to be trimmed.

Further, in trimming saddle-stitched or inserted work, on account of the roll of the back—that is to say, the increased thickness of the book at the stitched edge—where the 40 books are trimmed in batches of ten or more at a time, which is the practice, the top book will, as a rule, be larger than the other books, and the intermediate books will be progressively smaller toward the bottom of 45 the pile. Not only, therefore, are the books of irregular size, but this variation results in an unnecessary increase in postage on the second-class mail matter.

A further objection to this method of 50 procedure results from the fact that, in trimmers now on the market, the cutting knife acts against a wooden or lead cutting stick which, after short use, has a groove formed therein; and it accordingly becomes necessary to lower or adjust the knife to com-

pensate for the depth of the groove, otherwise the lowest or bottom book in the pile will not be trimmed through. The closest attention is required to insure that all the books are trimmed; and actually, in practice, 60 a large number of the bottom books from the various piles—especially on the continuous type of trimmer—have to be re-trimmed for this reason. Always some books have to be re-trimmed because the operator does 65 not know when to reset his knives or put in new cutting sticks until he sees that some books are not being trimmed. This involves the use of skilled operators, loss of time and considerable expense and annoyance. 70

By the use of the device of my present invention, each book is trimmed as it is delivered and trimmed as perfectly as though die-cut, and all the books are alike in size; the large number of cutting-machine operators and the truckmen heretofore employed are eliminated, with the result that they can be used for other necessary work, to say nothing of the great saving involved; the valuable floor space heretofore occupied 80 by great piles of untrimmed books is saved for other uses; no books have to be re-trimmed; and no additional operators, over those heretofore used in connection with the insetting machines alone, are necessary. As 85 a matter of fact, the girl who formerly stood at the delivery of the insetting machine to take off untrimmed books has simply moved to the delivery of the trimmer where she takes off trimmed books; or, if desired, the 90 books may be delivered to a conveyer which carries them direct to the mailing department, or other desired destination. In addition, the decrease in production of a book-forming machine, such as an insetting or 95 gathering machine, whether the books are inset or gathered manually or mechanically, equipped with the present invention, is negligible, and at the most not over two per centum. 100

The present invention will be better understood by reference to the accompanying drawings, illustrating one expression of the inventive idea, and wherein—

Figure 1 is a side elevation of the improved trimming mechanism; 105

Fig. 2 is a detail perspective view, illustrating the knife which trims the edge of the book opposite the fold, and its associated mechanism; 110

Fig. 3 illustrates the support and associated devices on which the books are deposited after they pass through the closing rollers which are arranged above the saddle;

Fig. 4 is a detailed perspective of the clamp which holds the book while the knife which trims the edge opposite the fold is operating, means for heading up or positioning the book for the second trimming, and associated mechanism;

Figs. 5 and 6 are detailed views of the gage or stop members which position the book for the first trimming;

Fig. 7 is a perspective view of the members which move the books into engagement with the first gage and which start the movement of the books after they have received the first trimming;

Figs. 8 and 9 are details of a tensioning device which operates on the upper feed belts to insure that the books shall be held against the second gage; and also coöperates with the header-up to position the book against said second gage;

Fig. 10 is a detailed perspective of the gage or stop members that assist the positioning of the books when they receive the second trimming, that is to say, when the top and bottom of the book are being trimmed;

Fig. 11 is a side view of the gage or stop members which stop the books for the second trimming;

Fig. 12 is a perspective view of the clamps which hold the book when it receives the second trimming;

Fig. 13 is a perspective view of the knives which effect the trimming of the top and bottom of the book, and their associated mechanism;

Fig. 14 is a detached view of one of said knives and its support; and

Fig. 15 is a detached perspective view of the delivery end of the trimmer.

Referring to the drawings, wherein like reference numerals indicate like parts, 20 represents a support of any suitable book-forming machine on which the books are formed. By way of illustration this support is here shown as a saddle such as illustrated in my Patents Nos. 1,177,524, 1,177,525 and 1,236,181, along which the signatures are fed and on which they are preferably assembled and suitably bound, as by wire stitching for example. The means for feeding the signatures along the saddle and binding the same are not shown, as any desired means for this purpose may be employed.

60 The books are delivered from the support or saddle and closed if necessary after they are bound. As here shown a vertically reciprocating blade 21 elevates the books into the bite of closing rollers 22 and 23, which latter deposit the closed books on suitable

supporting members folded edge foremost. The blade 21 is reciprocated by means of a bell-crank lever 24, pivoted at 25 to the frame of the machine. The short arm of said lever is engaged by a cam 26 keyed to shaft 27 (which is preferably a power shaft of the book-assembling machine); and the long arm of said lever is pivotally connected to the blade at 28. A spring 29 has one end secured to the long arm of said lever and the other end anchored to the base plate A of the machine. This spring acts to lower the blade 21 which is elevated to deliver the books to the closing rollers by the cam 26. A stop 30 positions the books on the support immediately over the elevating means.

15 Fig. 7 is a perspective view of the closing rollers 22 and 23 are mounted on shafts 31 and 33, respectively, carried by suitable bearings on the machine frame B. Shaft 31 carries a gear 34 which meshes with a gear 35 on shaft 33, so that the closing rollers rotate in the direction of the arrows, Fig. 1. These rollers are rotated from shaft 27 through the medium of a sprocket chain 36 which passes around a gear 37 on shaft 90 27 and around a pinion 38 on shaft 31.

20 The book when it leaves the closing rollers is deposited on supporting members (Fig. 3) constituted by a plurality of plates 39, 39^a, 39^b, and 39^c and fingers 40, 40^a and 40^b, all 95 of which are screwed or otherwise suitably secured to the framework of the machine. When in position on these plates and fingers, the books are under two guide members 41 and 41^a carried by a cross bar 42. The ends 100 of the fingers 40, 40^a and 40^b over which the books last passed on their way to the trimming mechanism are preferably slightly inclined upwardly.

25 Means are provided for positively engaging the books to remove them from said supporting members and to progress them into engagement with the first gage where the edge of the book opposite the fold is trimmed; and preferably two feeding mechanisms are employed one of which delivers the books, one at a time, to the other. The second feeding mechanism progresses the book into engagement with the first gage, and preferably this second feeding mechanism is driven at a higher speed than the first, so that the movement of the book is suddenly increased when it comes under the influence of the second feeding mechanism.

30 As here shown, the books are removed from said support by means of a pair of endless chains 43 and 43^a, which are provided respectively with a single lug or finger 44 and 44^a, which lugs or fingers engage the rear edge of the book after it has come 125 through the closing rollers and positively progress the same into engagement with the second set of feeding mechanisms. Said endless chains 43 and 43^a pass around sprocket wheels 45 and 45^a keyed to a shaft 130

46 and around similar sprocket wheels (not shown) keyed to shaft 31. The movement of said chains is timed with the operation of the vertically-reciprocating blade 21; that is to say, the lugs or fingers 44 and 44^a move into engagement with the edge of the book opposite the fold as soon as the book is deposited on said support by the closing rollers.

10 The chains 43 and 43^a feed the books into the bite of rollers 47 and 48 and belts 49, 50 and 51 on the one hand (Fig. 7), and rollers 52 and 53 and belt 54 on the other hand. As will be observed, rollers 52 and 53 and belt 54 engage the upper surface of the book, roller 52 coöperating with lower roller 47 and roller 53 coöperating with lower roller 48. Belt 54 coöperates with lower belt 50. These belts and rollers, as well as belts 49 and 51, are driven at a greater speed than are chains 43 and 43^a, the result being that the books are rapidly moved away from lugs 44 and 44^a, which latter, accordingly, freely clear the books as they pass downwardly around the sprocket wheels 45 and 45^a. This speeding up of the books also has the advantage of expediting the work and conducing to an increased capacity for the machine. The rollers 52 and 53 are adjusted with respect to their coöperating rollers 47 and 48, so that the books are firmly held therebetween, and are positively and rapidly moved into engagement with the gage members 57 and 58, Fig. 5, against which they are positioned for trimming the edge of the book opposite the fold. It is pointed out that the rollers 52 and 53 do not grip the upper surface of the book close enough to buckle the cover of the same.

20 Further, guide rods 59, which are vertically adjustable on the framework, also act to prevent any buckling.

In order to effect accurately the positioning of the books against the gage, dogs 60 and 61 are provided. As will be observed from an inspection of Fig. 3, the books pass over these dogs as they are removed from the supporting members by chains 43 and 43^a, and as soon as the edge of the book opposite the fold passes over the nose of said dogs 60 and 61, the latter are reciprocated forward in the path of movement of the books and in engagement with the edge of the same. This not only 30 effects the positioning of the books, but prevents any rebound which the books would otherwise have when they hit the gage members. Preferably the engaging noses or ends 60' and 61' of these dogs or abutments are pivoted and spring-pressed, so that, should the machine become clogged at this point, the noses will yield and prevent breakage.

These dogs are operated from shaft 62 by suitable connections, as here shown cranks

63 and 63' of which are adjustably mounted on shaft 62, being connected at their free ends respectively with links 64 and 64', which latter are pivoted to said dogs or abutments. The cranks 63 and 63' are made adjustable in order to vary the movement of said dogs or abutments when necessary or desirable. The shaft 62 is oscillated from shaft 65 through cam 66, slotted arm 67 carrying a roller 68, which latter engages cam 66, and a crank 69 carried by shaft 62. The dogs 60 and 61 are moved forwardly, that is to say, in the direction of movement of the books, by means of a spring 70, which encircles rod 71. This rod is connected to shaft 62 by means of a crank arm 72. The upper end of said spring engages a collar 73 carried by said rod, and the lower end of the spring abuts the base of the machine. The cam 66 acts to move the dogs 60 and 61 rearwardly. Shaft 65 is driven from main shaft 74 through a gear 75 on the main shaft meshing with a gear 76 on shaft 65.

The gage hereinbefore referred to, and against which the book is positioned for the trimming of the edge opposite the fold, is illustrated in detail in Figs. 5 and 6. As there shown, the gage members 57 and 58 are identical in construction, and are rocked into and out of the path of movement of the books. Each of these gage members is pivoted on a pin 77 carried by a bracket arm 78, which is adjustable lengthwise of the machine by means of the bolt and slot connection 79, in order to accommodate books of various sizes. The lower ends of two links 80 and 80' are connected to the gage members, and the upper ends of the same to cranks 81 and 81' carried by and adjustable around and along shaft 82, which latter is oscillated by a cam 83 on main shaft 74 through link 84 and crank arm 85. A spring 86 causes the gage members to be swung into the path of the books, and said members are elevated out of the path of the books by cam 83. The upper end of said spring abuts a stop 87 secured to the machine frame, and the lower end of the spring engages a pivoted block 88 carried by the link 84.

When the book is positioned against the gage members 57 and 58, as heretofore described, a clamp 89 descends into engagement with the book to firmly hold the same while the edge of the book opposite the fold is trimmed. This clamp is illustrated in Figs. 1 and 4. As shown, the same is vertically reciprocated in a casting 90 mounted on the framework B of the machine, the end portions 91 and 91' of said clamp engaging slide-ways in said casting. The clamp is elevated by means of a cam 92 on the main shaft 74 operating through slotted arm 93 carrying a roller 94, which rides on said cam 92, the upper end of said

arm being connected to a crank 95 carried by shaft 96. Shaft 96 has keyed thereon two other cranks 97 and 97' to the free end of which are connected reach-rods 98 and 98'. The other end of each of said reach rods is suitably secured to the ends of the clamp 89.

The clamp 89 is pressed yieldingly but firmly into engagement with the book by suitable means, here shown as springs 99 and 100. The spring 99 encircles a rod 101, one end of which passes loosely through a base 102, against which one end of said spring abuts. The other end of the spring 15 engages collar 103 on said rod 101, and the other end of said collar is carried by a block 104, which is pivoted to the lower end of an arm 105 keyed to shaft 96. The spring 100 encircles rod 106, one end of which engages 20 a perforated stop 107 fixedly mounted on the framework, and through which the rod 106 loosely passes. The other end of said spring engages a collar 108 on the rod 106. One end of said rod 106 is fixedly secured in 25 a block 109 pivoted to the lower end of an arm 110, the other end of which arm is keyed to shaft 96. It will therefore be seen that when, under the influence of cam 92, the shaft 96 is oscillated and the clamp 89 is elevated, the springs 99 and 100 will be compressed and that, when the low part 92' of the cam is engaged by roller 94, the springs 99 and 100 will expand, thus lowering the clamp 89 into firm but yielding engagement 30 with the book.

The knife which effects the trimming of the edge of the book opposite the fold is a vertically reciprocating knife 111 (Fig. 2) of the inclined guillotine type, and is 40 mounted on a carrier 112 on which it has vertical adjustment by means of bolt and slot connections 113. This knife coöperates with a lower knife 111' mounted on a cross-beam. The downward movement of the 45 knife to effect the cutting or trimming is secured in a positive manner through the medium of links 114 and 114' connected to cranks 115 and 115', which latter are keyed to shaft 65.

50 The edge of the book opposite the fold has now been trimmed by a clean shearing cut, the book being held clamped and absolutely stationary at the time the cutting is effected.

55 As above indicated, the books are moved into engagement with the gage members 57 and 58 by rollers 47 and 48 and belts 49, 50 and 51, which engage the underside of the book, and rollers 52 and 53 and belt 54 which 60 engage the upper surface of the book. These same means are utilized to initiate the movement of the books on their way to the second trimming mechanism, as soon as the gage members 57 and 58 are swung out of 65 the path of movement of the books.

In order to insure positive forward feed of the book at this time, means are provided for slightly lowering the rollers 52 and 53 and belt 54 into gripping engagement with the top of the book.

This movement of said belt and rollers is effected by mounting the same on a frame which is pivoted on a shaft 116, which latter is oscillated by a cam 117 provided with a slight depression 118, the oscillating movement being transmitted to said shaft 116 by means of a slotted arm 119 and crank arm 120. This crank is connected to the shaft 116 through the medium of a sleeve 121 through a bolt and slot connection 122, 75 so that said crank may be adjusted to vary the degree of oscillation of said frame and thus compensate for books of various thicknesses. The crank 120 is secured in its adjusted position by adjusting screws 123 and 80 124 passing through flanges on said sleeve 121. The slotted arm 119 is provided with a roller 125 which rides the cam 117. Said arm is raised by the cam 117 to elevate rollers 52 and 53 and belt 54, and is lowered by 85 means of a spring 126 encircling a rod 127, one end of which spring engages an abutment 128 on the frame of the machine and the lower end of which rests against a set-collar 129 carried by said rod 127 which is 90 connected to arm 119.

The oscillating frame is made up of arms 130 and 131, adjustably mounted on shaft 116, and constituting bearings for a shaft 132; and arms 133 and 134, adjustably 100 mounted on shaft 116 and constituting bearings for shaft 135. The rollers 52 and 53, as well as a belt pulley around which belt 54 passes, are mounted on shaft 132; and shaft 133 carries two belt pulleys around which 105 pass belts 55 and 56, which latter are arranged above and coöperate with lower belts 49 and 51. In the position of the parts indicated in Fig. 7, the roller 125 is riding the unbroken surface of cam 117 and belts 110 55 and 56 are in gripping engagement with a book. As soon as the roller 125 enters depression 118 the frame is oscillated and the rollers 52 and 53 and belt 54 are lowered into gripping engagement with the book. This gripping by rollers 52 and 53 and belt 54 is only effected when it is desired to initiate the movement of a book which has been immobilized to effect the trimming of the 115 edge opposite the fold.

The oscillation of the frame is very slight, the difference being simply that between the book when compressed and when uncompressed; that is to say, when the rollers 52 and 53 engage the book to feed it into engagement with the gage members 57 and 58, the rollers do not compress the book. But after the first cut has been made and it is desired to give the book an initial impulse forward, roller 125 drops into depression 120 125 130

118 with the result that the rollers 52 and 53 descend into gripping engagement with the upper surface of the book and compress the same. Immediately after the movement 5 of the book is initiated the roller 125 rides onto the unbroken surface of the cam 117, whereupon rollers 52 and 53 pass out of gripping engagement with the book, and belts 55 and 56 are oscillated into gripping 10 engagement to feed the same forward into contact with a second set of gage members where the top and bottom of the book are trimmed.

Before describing in detail the mechanism 15 for effecting the trimming of the top and bottom of the books, the circuit and drive of the lower and upper belts will be described.

As clearly shown in Figs. 1, 7 and 15, the 20 lower belts 49, 50 and 51 pass around belt pulleys on a shaft 136 carried by arms 136' pivoted in bearings 137, which shaft 136 is arranged immediately below shaft 132. The lower belts then pass around a knurled 25 part of shaft 138, mounted in suitable bearings, at the delivery of the machine (Fig. 15), thence around a tension roller 139 (Fig. 1), idler roller 140, and thence back to the pulleys on shaft 136. The tension 30 rollers 139 are carried by a swinging frame pivoted at 141, to which frame a tensioning weight 142 is attached. The said lower belts are driven from shaft 138 which carries a bevel gear 143 meshing with a bevel gear 144 on one end of a rearwardly inclined 35 shaft 145, the other end of which shaft carries a bevel gear 146 meshing with a similar bevel gear 147 on short shaft 148 mounted in the frame of the machine. This shaft 40 147 carries a pinion 149 with which meshes a gear 150 mounted on shaft 151. Shaft 151 carries a pinion 152 that meshes with a gear 153 carried by shaft 154 mounted in the frame of the machine (Fig. 1).

45 The upper belts 54, 55 and 56, which, like the lower belts 49, 50 and 51, are endless, pass rearwardly along the machine around an idler shaft 155 (Fig. 1), thence around tensioning rollers 156 mounted on an 50 adjustable frame 157, the position of which may be varied by means of adjusting bolts 158. Said belts then pass around pulleys 159, 160 and 161 (Fig. 15) carried by shaft 162, belts 55 and 56 then passing around 55 the pulleys on shaft 135 on the oscillating frame, and belt 54 then passing around its pulley on shaft 132.

The shaft 162 is driven from shaft 138 through a train of gears. A gear 163 carried 60 by shaft 138 meshes with a small idler 164 carried on a stub shaft which in turn meshes with an identical idler 165 carried on a second stub shaft, said idler 165 meshing with a gear 166 on shaft 162, gear 166 65 being of the same size as gear 163. This gear

drive between shafts 138 and 162 insures that the upper and lower belts shall be driven at the same speed. Further, it will be observed that shaft 162 has bearings in blocks 167 and 168 that slide vertically in 70 a casting 169 mounted on the frame of the machine; said blocks 167 and 168 being yieldingly held in position by springs 170 and 170', the other ends of said springs engaging a plate 171 carried by said casting 75 169. Shaft 162 may, accordingly, yield if necessary; and the arrangement of gears described insures that shafts 138 and 162 shall always remain in gear even though shaft 162 should be displaced.

80 After the book has received the first trimming, it is moved along the machine as heretofore described by means of the upper belts 54, 55 and 56, and lower belts 49, 50 and 51, until it contacts with a second gage 85 which, as here shown, is constituted by stop members 172 and 173 (Fig. 10) mounted on a stub shaft 174. Through suitable connections these members are elevated into and depressed out of the path of movement of 90 the books. As here shown, said gage or stop members may be adjusted both lengthwise of the machine and laterally thereof for books of various sizes. The stub shaft 174 passes through openings in the forward 95 ends of supporting arms 175 and 176, which latter in turn are adjustable on a pair of plates 177 by means of bolt and slot connections 178. The plates 177 are laterally adjustable along the framework of the machine in a slot 179, a squared portion 177' on said plate engaging in said slot 179. The bolts 178 project through said slot 179 and into a second slot 180 arranged therein. The plates 175 and 176 are securely held in 100 their adjusted position by means of the bolt and slot connections 178, and also by means of screw members 181 which pass through vertical ears on plates 177.

110 The gage or stop members 172 and 173 are rocked on stub shaft 174 from shaft 182 through cranks 183 and 183' and links 184 and 184', and said shaft 182 is rocked from shaft 154 through a cam 185 engaging a roller 186 on a slotted arm 187, the upper end 115 of which is connected to a crank 188 on said shaft 182. The cranks 183 and 183' are adjustable lengthwise of said shaft 182 for books of various sizes, and the cam 185 is also adjustable lengthwise of the shaft 154 120 for the same purpose. The cam 185, through the connections described, acts to lower the stop or gage members 172 and 173 out of the path of the book, and said members are moved into the path of the book to 125 stop the same by means of a spring 189 which encircles a rod 190. One end of said spring engages a stud 191 fixed on the frame of the machine, and the other end a set-collar on said rod 190. One end of said rod 130

190 is loosely connected to a crank 192 keyed to the shaft 182.

To insure a firm engagement of belts 55 and 56 with the upper surface of the book to positively feed the same along into engagement with said gage members 172 and 173, and also to insure an exact positioning of the books against said gage members so that the trimming of the top and bottom of the books shall be accurately performed, there are provided a pair of tensioning devices, here shown as rollers 193 and 193' (Fig. 9) which are positioned to press upon the edge of the book already trimmed, that is, the edge opposite the fold, when the folded edge of the book engages the gage members. To secure this latter result these tensioning devices coöperate with a header-up, as hereinafter described. The two devices are identical, the device provided with roller 193 being mounted between the upper and lower reaches of belt 55 and that provided with roller 193' between the upper and lower reaches of belt 56. These tensioning devices act on the books through the lower reaches of said belts and, in the positioning of the books and preventing of rebound of the same when the books hit the second gage members, perform substantially the same function as that of the dogs or abutments 60 and 61 with respect to gage members 57 and 58.

As shown in Figs. 1, 8 and 9, each of these tension devices is carried by a guide rod 195 which in turn is supported by a cross arm 196 on the frame of the machine. These guide rods 195 are arranged above the book when it is in position for the second trimming and assists in preventing buckling of the cover.

Each of the tensioning rollers 193 and 193' is carried by an arm 197 mounted loosely on a stud 198 carried by a split support 199 on rod 195. A spring 200 encircles the stud 198 and one end of said spring is fixedly secured to arm 197. The other end of said spring passes through an opening in a knurled member 201. This member 201 is held in position by a pin 202 engaging in depressions 203 in said member. When it is desired to alter the tension of said roller 193, the member 201 is pressed inwardly against the tension of spring 200 until the pin 202 clears the depressions 203, whereupon the member 201 is rotated a half turn and the pin is again engaged with the depressions 203, thus holding the member in its adjusted position. The split support 199 is adjustable along the rods 195 and is held in adjusted position by means of a winged nut 204.

At this time when the folded edge of the book is in contact with the gage members 172 and 173 and the tension rollers are pressing on the trimmed edge of the book, a

header-up 205 (Fig. 4) is moved into engagement with one of the edges of the book adjacent the fold—the top or bottom of the same—and, coöperating with the tension rollers which are pressing along the trimmed edge of the book, moves the latter to the exact position desired for trimming. This header-up is operated from main shaft 74 through a cam 206. A slotted arm 207 carries a roller 208 which engages said cam, and the upper end of said arm is connected to a crank 209 mounted on shaft 210 which is provided with a second crank 211, which latter has an adjustable connection at 212 with a rod 213 on which the header-up 205 is carried. The cam 206 acts to move the header-up away from the book, and a spring 214 is provided to move the header-up into yielding engagement with the book. Said spring encircles a rod 215, the lower end of which projects into an opening in the framework of the machine. The lower end of said spring 214 abuts said framework and the upper end engages a collar 216 carried by said rod. The upper end of the rod is connected to a crank 217 keyed to shaft 210. It will therefore be seen that, when the header-up is moved away from the book, under the influence of cam 206, the spring 214 is compressed, so that the header-up is moved into yielding engagement with the book by said spring when the roller 208 passes over the low part of the cam.

The book has now been exactly positioned against the gage members 172 and 173 by the conjoint action of the tension rollers 193 and 193' and the header-up 205 and immediately clamps 218 and 218' are moved into firm but yielding engagement with the upper surfaces of the book to hold the same while the top and bottom thereof are being trimmed. These clamp members are carried by a cross beam 219, the ends of which are provided with bearing surfaces 220 and 220' that engage slideways provided in casting 221 (Fig. 1) carried by standards 222 and 223 on the main frame of the machine. The clamps are moved upwardly out of engagement with the books by a cam 224 (Fig. 10) mounted on shaft 154. A roller 225 carried in one end of an arm 226 rides said cam, and the other end of said arm is secured to a rock shaft 227. Keyed to each end of this rock shaft 227 are bell-crank levers 228 and 228'. To one arm of each of said levers is secured the lower end of a reach-rod 229, the upper end of each of said reach-rods being pivotally connected to the cross bar 219 that carries the clamps 218 and 218'. The other arm of each of said bell-crank levers 228 and 228' is provided with a perforated block 230 which is pivotally secured to said lever by means of a stud 231. A rod 232 passes through each of said blocks 230 and carries a spring 130

233, one end of which engages against a set-collar 234 carried by the rod 232 and the other end of which engages an abutment 236 carried by the base of the machine, said rod 5 232 sliding through said abutment 236. It will therefore be seen that the clamps are elevated out of engagement with the books by means of the cam and are forced into yielding engagement with the books by 10 means of the springs 233. Said clamps are adjustable along bar 219 and are held in adjusted position by means of set-screws 237 and 237'.

After the clamps have engaged the books, 15 knives 238 and 238' trim the top and bottom of the same. These knives are carried by a heavy rectangular frame 239, which frame is elevated and lowered by means of a pair of cranks 240 and 240' mounted on shaft 154, 20 and an identical pair of cranks 241 and 241' mounted on a shaft 242. Each of the cranks 240, 240', 241 and 241' is connected to one corner of the rectangular frame 239 by means of reach-rods 243 whereby a powerful 25 and uniform upward and downward movement is imparted to the four corners of the frame. The frame has bearing surfaces 239' that engage corresponding surfaces on standards 222 and 223 provided with suitable gibbs for taking up wear in both directions. Shaft 242 carries a gear 244 similar to gear 153, the latter being driven from gear 244 through the intermediary of an idler gear 245. Gear 244 is driven from the 30 main shaft 74 through an idler gear 246 (see Fig. 1).

Each of the knives 238 and 238' is mounted on knife-carriers 247 (Figs. 13 and 14) which are laterally adjustable for different 40 sizes of books along slots 248 and 249 by means of stay bolts 250. The knives 238 and 238' are vertically adjustable to compensate for wear, and preferably there is interposed between each knife and its carrier 247, an 45 intermediate plate 251 which is adjustably secured to said plate 247 by means of bolts 252, said bolts passing through slots 253 in the carriers 247 and slots 254 in the intermediate members 251. The bolts 252 likewise engage in screw-threaded openings 255 in the knife blades. In order to hold the blades fixedly in their adjusted position, set bolts 256 pass through screw-threaded openings 257 in a flange 258 of the intermediate 50 member 251 and engage the top edge of the knife blade. These bolts may be manipulated through cut-out portions 259 provided in the knife carriers 247.

The knives are of the usual inclined guillotine type whereby a shearing and perfect cut is assured, and coöperate with appropriate bottom knives 238^a (Fig. 9).

As soon as the knives 238 and 238' perform their trimming function and the 65 clamps 218 and 218' are raised from the

book, the stop members 172 and 173 are then rocked downwardly out of the path of movement of the same, and the book is rapidly moved toward the delivery end of the machine by the belts, and passes outwardly between shafts 138 and 162 onto any suitable or desired delivery. 70

If the described trimming mechanism is used in association with insetting or gathering machines, such as disclosed in my said 75 patents, the main shaft 74 is driven from the drive mechanism of said insetting or gathering machine, so that the trimmer and the book-forming machine are timed to operate in unison; that is to say, the books are delivered from the saddle or support 20 in 80 timed relation to the various operations of the trimming mechanism. As shown in Fig. 1, a bevel gear 260 on a stub shaft 261 meshes with a similar bevel gear on shaft 74. Said 85 stub shaft carries a large spur gear 262 which in turn meshes with a gear, such as gear 20 of Fig. 2 of my Patent No. 1,177,524.

While the trimming mechanism has only been illustrated in association with one form 90 of book-making machines, to wit, an inserter, it can be used in connection with practically all forms of book-making machines; and, further, it can advantageously be used alone as a separate, independent machine to 95 which untrimmed books are fed manually by an operator.

It will be noted that when each of the trimming acts takes place, the book being operated upon is immobilized and clamped 100 in position as the guillotine knives effect the trimming. This insures the most perfect results in the trimming, obviating the disadvantages that follow from moving books past the knives or the knives past the 105 books. At the same time the device of the present invention keeps up the speed of production so that the books are trimmed as fast as they are produced and bound; and, when it is borne in mind that the books are 110 delivered from the saddle 20 at the rate of sixty to the minute, it will be apparent that a great problem has been solved.

The operation of the device is as follows:

The books are assembled and bound on 115 the saddle 20 along which they are fed until delivered therefrom by the vertically-reciprocating blade 21. The rollers 22 and 23 close the same and deposit them on the supporting members shown in Fig. 3, from 120 which they are promptly removed by the engagement therewith of lugs 44 and 44^a carried by sprocket chains 43 and 43^a. These chains deliver the books, folded edge foremost, into the bite of the upper and lower 125 rollers and belts shown in Fig. 7, which latter are driven at a higher speed than the chains 43 and 43^a and, accordingly, rapidly withdraw the books from said chains so that the lugs 44 and 44^a freely clear the rear edge 130.

thereof. The belts and rollers referred to progress the books into contact with the gage members 57 and 58 (Fig. 5) against which each book is exactly positioned by 5 means of the dogs or abutments 60 and 61 which engage the edge of the book opposite the fold as soon as said edge drops down in front of said dogs or abutments. As soon as the book is positioned the clamp 89 engages the book and thereupon the knife 111 coöperating with lower knife 111' descends and trims the edge of the book opposite the fold.

After the knife 111 and the clamp 89 have 15 been elevated out of engagement with the book, the gage members 57 and 58 are rocked out of the path of movement of the book, whereupon the rollers 52 and 53 and belt 54 are lowered into gripping engagement with 20 the upper surface of the book to give the same an initial impulse forward toward the second trimming mechanism. This gripping is only momentary and sufficient to start the book forward, following which the 25 belts 55 and 56 are lowered into gripping engagement with the book and feed the same into engagement with gage members 172 and 173. The tension rollers 193 and 193' act to prevent rebound of the book as the same 30 hits the gage members, said members pressing upon the trimmed edge of the book when the folded edge contacts the gage. At this moment the header-up 205 (Fig. 4) engages one of the edges of the book adjacent 35 the fold and, coöperating with the tension rollers 193 and 193' exactly positions the book against the gage members 172 and 173. Thereupon the clamps 218 and 218' descend into engagement with the upper surface of 40 the book, following which the knives 238 and 238', acting in conjunction with their associated lower knives, trim the top and bottom of the book.

Thereafter the knives and clamp are elevated, the gage members are depressed out 45 of the path of movement of the book, and the latter is progressed by the belts outward between shafts 138 and 162 onto any suitable or desired delivery.

50 It will be observed that the knives are set and constructed to operate simultaneously, and that the forward and rear gage members are also set and constructed to operate simultaneously. The whole timing of the 55 machine is 1 to 1, so that the books pass rapidly through the trimmer. During the normal operation of the machine, on a book of the size of the "Saturday Evening Post," for example, there will be one book against 60 the forward gage, a second book against the rear gage, a third book between the upper and lower belts that is just about to leave the trimmer, and a book that is being elevated between the closing rollers.

65 As heretofore indicated, the trimmer of

the present application can be used in association with practically all forms of book-forming machines, such as gathering and in-setting machines, the so-called "perfect binder," etc.; and while, for the sake of clearness, one expression of the inventive idea has been illustrated and described in considerable detail, it will be understood that the invention is not limited thereto, but that the inventive idea is susceptible of expression in various mechanical embodiments within the limits of the appended claims.

What is claimed is:—

1. In combination, a saddle on which books are assembled and bound, means for elevating the books from said saddle and closing the same, and means for trimming the edges of each book as it is delivered, said trimming mechanism operating in timed relation with said mechanism for delivering the books from the saddle.

2. In combination, a saddle on which books are assembled and bound, means for elevating the books from said saddle and closing the same, and means for trimming the edges of each book as it is delivered comprising a reciprocating knife for trimming the edge of the book opposite the fold, and a pair of reciprocating knives for trimming the two edges adjacent the fold, said trimming mechanism operating in timed relation with said mechanism for delivering the books from the saddle.

3. In combination, a saddle along which books are conveyed, means for elevating the books from said saddle and closing the same, and knives for trimming the edge of each book as it is delivered, said trimming knives operating in timed relation with said mechanism for delivering the books from the saddle.

4. In combination, a saddle on which books are assembled, means for delivering the books from the saddle and closing the same, a gage movable into and out of the path of movement of the books, means progressing each book as it is delivered into engagement with said gage, a movable abutment holding said book against said gage, and a vertically reciprocating knife for trimming the edge of the books opposite the fold.

5. In combination, a support on which books are assembled and bound, a gage movable into and out of the path of movement of said books, an endless chain provided with means in the form of a lug for engaging one edge of the book to move the same toward said gage, additional means engaging the book to move it into contact with said gage, reciprocating means holding the book in engagement with said gage, and means for trimming the edge of the book opposite the fold.

6. In combination, a saddle on which books are assembled and stitched, closing

- rolls arranged above said saddle, means for elevating said books into the bite of said closing rolls, a gage movable into and out of the path of movement of said books, means 5 moving said books into engagement with said gage, a vertically reciprocating knife for trimming the edge opposite the fold, and feed rollers movable into gripping engagement with the top of said book to move the 10 same after the operation of said knife.
7. In combination, a support for untrimmed books, a gage movable into and out of the path of movement of said books, means for trimming the edge of the book opposite the fold when it is in contact with said gage, a pivoted frame, two sets of book-feeding means carried thereby, and means for rocking said frame to successively move said book progressing means into gripping 15 engagement with said book.
8. In combination, a support for untrimmed books, a gage movable into and out of the path of movement of said books, means for trimming the edge of the book opposite the fold when it is in contact with said gage, a pivoted frame, two sets of book-feeding means carried thereby, and means for rocking said frame in one direction to move one set of feeding means into gripping 20 engagement with the book to initiate the movement of the same after the operation of said knife and in the opposite direction to engage the second set of feeding means with said book.
9. In combination, a support for untrimmed books, a gage movable into and out of the path of movement of said books, a conveyer provided with means for engaging the book to move the same toward said 25 gage, a second conveyer driven at a higher speed than said first-mentioned conveyer and receiving the books therefrom and progressing the same into contact with said gage, and means for trimming the edge of the book opposite the fold.
10. In combination, a support for untrimmed books, a gage movable into and out of the path of movement of said books, an endless conveyer provided with a lug for 30 engaging one edge of the book to move the same toward said gage, a second endless conveyer driven at a higher speed than said first-mentioned conveyer receiving said books and moving them rapidly out of the path of said lug and into contact with said gage, and means for trimming the edge of the book opposite the fold.
11. In combination, a support for untrimmed books, a gage movable into and out 35 of the path of movement of the books, means moving the books into engagement with said gage, a moving member coöperating with said gage to position the book against said gage, and a knife for trimming the edge of the book opposite the fold.
12. In combination, a support for books to be trimmed, a gage movable into and out of the path of movement of the books, means moving the books into engagement with said gage, a member moving in the line of movement of the books over 40 which the books are fed coöperating with said gage to position the book against said gage, and a knife for trimming the edge of the book opposite the fold.
13. In combination, a support for books to be trimmed, a gage movable into and out of the path of movement of the books, means moving the books into engagement with said gage, a reciprocating member moving in the line of movement of the books over 45 which the books are fed coöperating with said gage to position the book against said gage, and a knife for trimming the edge of the book opposite the fold.
14. In combination, a support for untrimmed books, a gage movable into and out of the path of movement of the books, means moving the books into engagement with said gage folded edge foremost, a moving member coöperating with said gage to position the book against said gage, and a knife for trimming the edge of the book opposite the fold. 50
15. In combination, a support for books to be trimmed, a gage movable into and out of the path of movement of the books, means moving the books into engagement with said gage folded edge foremost, a member moving in the line of movement of the books coöperating with said gage to position the book against said gage, and a knife for trimming the edge of the book opposite the fold. 55
16. In combination, a support for books to be trimmed, a gage movable into and out of the path of movement of the books, means moving the books into engagement with said gage folded edge foremost, a reciprocating member moving in the line of movement of the books over which the books are fed coöperating with said gage to position the book against said gage, and a knife for trimming the edge of the book opposite the fold. 60
17. In combination, a support for books to be trimmed, a gage movable into and out of the path of movement of the books, means moving the books into engagement with said gage folded edge foremost, a member moving in the line of movement of the books engaging the edge opposite the fold and coöperating with said gage to position the book against said gage, and a knife for trimming the edge opposite the fold. 65
18. In combination, a gage, book-progressing means engaging each book and moving it into engagement with said gage, a knife for trimming the edge of the book opposite the fold, and means operating after said trimming for moving said book. 70

progressing means into gripping engagement with the book to initiate a further movement of the book.

19. In combination, a gage, book-progressing means engaging each book and moving it into engagement with said gage, a knife for trimming the edge of the book opposite the fold, means momentarily operating after said trimming for moving said 10 book-progressing means into gripping engagement with the book to initiate a further movement of the book, and additional means for continuing the movement of the book.

20. In combination, a gage, book-progressing means for moving books into engagement therewith, a device pressing on each book along the edge opposite that which is in engagement with said gage, and means for trimming the edges of the book 20 adjacent the fold.

21. In combination, a gage, book-progressing means engaging each book and moving it into engagement with said gage folded edge foremost, a knife for trimming 25 the edge of the book opposite the fold, and means operating after said trimming for moving said book-progressing means into gripping engagement with the book to initiate a further movement of the book.

30 22. In combination, a gage, book-progressing means engaging each book and moving it into engagement with said gage folded edge foremost, a knife for trimming the edge of the book opposite the fold, means 35 momentarily operating after said trimming for moving said book-progressing means into gripping engagement with the book to initiate a further movement of the book, and additional means for continuing the movement of the book.

23. In combination, a gage, book-progressing means for moving books into engagement therewith folded edge foremost, a device pressing on each book along the edge 45 opposite the fold when the book is in engagement with said gage, and means for trimming the edges of the book adjacent the fold.

24. In combination, a gage, book-progressing means for moving books into engagement therewith, a device pressing on each book along the edge opposite that which is in engagement with said gage, a header-up coöperating with said device to 50 position the book, and means for trimming the edges of the book adjacent the fold.

25. In combination, a gage, book-progressing conveyers for moving books into engagement therewith folded edge foremost, 60 a device engaging said conveyers and pressing on each book along the edge opposite the fold when the book is in engagement with said gage, and vertically reciprocating knives for trimming the edges of the book 65 adjacent the fold.

26. In combination, a gage, book-progressing means for moving books into engagement therewith folded edge foremost, a device pressing on each book along the edge opposite the fold when the book is in engagement with said gage, a header-up engaging one of the edges to be trimmed, said header-up coöperating with said device to position the book against said gage, and means for trimming the edges of the book 75 adjacent the fold.

27. In combination, a gage, book-progressing conveyers for moving books into engagement therewith folded edge foremost, a device engaging said conveyers and pressing 80 on each book along the edge opposite the fold when the book is in engagement with said gage, a header-up engaging one of the edges to be trimmed, said header-up coöperating with said device to position the book 85 against said gage, and vertically reciprocating knives for trimming the edges of the book adjacent the fold.

28. In combination, a gage, book-conveying means progressing each book into contact with said gage folded edge foremost, a movable device engaging the book and acting to position the same against said gage, a knife for trimming the edge opposite the 90 fold, a second gage into engagement with which each book is progressed, a device pressing on the trimmed edge when the folded edge engages said second gage, and knives for trimming the edges adjacent the fold.

29. In combination, a gage, book-conveying means progressing each book into contact with said gage folded edge foremost, a movable device engaging the book and acting to position the same against said gage, a knife for trimming the edge opposite the 105 fold, a second gage into engagement with which each book is progressed, a device pressing on the trimmed edge when the folded edge engages said second gage, a header-up engaging one of the edges to be trimmed 110 and coöperating with said device to position the book against said second gage, and knives for trimming the edges adjacent the fold.

30. In combination, a gage, book-conveying means progressing each book into contact with said gage folded edge foremost, a movable device engaging the book and acting to position the same against said gage, a knife for trimming the edge opposite the 115 fold, and mechanism operating after said trimming to cause said book-conveying means to grip each book to initiate the further movement of the same.

31. In combination, a gage, book-conveying means progressing each book into contact with said gage folded edge foremost, a movable device engaging the book and acting to position the same against said gage, a knife for trimming the edge opposite the 120 125 130

- fold, mechanism operating after said trimming to cause said book-conveying means to grip each book to initiate the further movement of the same, a second gage into engagement with which each book is progressed, a device pressing on the trimmed edge when the folded edge engages said second gage, and knives for trimming the edges adjacent the fold.
- 10 32. In combination, a gage, book-conveying means progressing each book into contact with said gage folded edge foremost, a movable device engaging the book and acting to position the same against said gage, 15 a knife for trimming the edge opposite the
- fold, mechanism operating after said trimming to cause said book-conveying means to grip each book to initiate the further movement of the same, a second gage into engagement with which each book is progressed, a 20 device pressing on the trimmed edge when the folded edge engages said second gage, a header-up engaging one of the edges to be trimmed and coöperating with said device to position the book against said second 25 gage, and knives for trimming the edges adjacent the fold.

In testimony whereof I have signed this specification.

EDWARD R. KAST.
